attys.

UNITED STATES PATENT OFFICE.

GEORGE A. STILES, OF BROOKLINE, ASSIGNOR TO JUSTUS W. FRENCH, OF LYNN, MASSACHUSETTS.

SEWING-MACHINE.

SPECIFICATION forming part of Letters Patent No. 443,655, dated December 30, 1890.

Application filed May 12, 1890. Serial No. 351,474. (No model.)

To all whom it may concern:

Be it known that I, GEORGE A. STILES, of Brookline, county of Norfolk, State of Massachusetts, have invented an Improvement in 5 Sewing-Machines, of which the following description, in connection with the accompanying drawings, is a specification, like letters and figures on the drawings representing like parts.

10 This invention relates to what is known as "wax-thread sewing-machines," my particular invention therein being in a peculiar construction of the post and presser-foot, whereby the same is adapted to hold the material to 15 be stitched together—as, for instance, the upper and a part of a sole when making a shoe after what is called the "French process," as fully described in United States Patent No. 379,640, dated March 20, 1888. I have also 20 provided the machine with a cutter by which to trim the edge of the upper and sole parallel to the line of stitching uniting them.

Figure 1, in front elevation, shows a sufficient portion of a wax-thread sewing-machine 25 with my improvements added to enable the same to be understood; Fig. 2, a left-hand side view of part of the machine shown in Fig. 1; Fig. 3, a top or plan view of the post; Fig. 4, a top or plan view of the foot; and Fig. 30 5, an enlarged section of the rest and foot, together with a last, a sole and upper thereon in section, and a needle, to thus show the parts in working position.

The frame-work A, including the overhanging arm A', (but partially shown,) the awl-bar A², having the awl a, the presser-bar B, the spring B' to keep the presser-bar down, the rocking frame C, on which slides the needle-bar b, having the needle b', and the cast-off bar c, having the cast-off c', the link c², the arm c³, the rock-shaft c⁴ for moving the needle-bar, the arm d of the rock-shaft d' to reciprocate the awl-bar, are and may be all as 40 common in wax-thread sewing-machines now 45 commonly in use and known to the trade as the "National."

In accordance with my invention I have added to the presser-bar of this usual form of wax-thread machine a presser e, having a 50 thin narrow foot e' and a hooked toe e², the

needle in its passage through the material and when feeding the same while the frame C is rocked traveling in the slot e³. The post f as remodeled for the work to be done on this machine has a very narrow throat or rest 55 2, provided with a projection 3 at one end of the recess or slot 4.

In the manufacture of shoes after what is known as the "French process" and as provided for in said United States patent, the inner sole is slotted in from its edge at two places between the toe and shank thereof, and a portion of the said sole between the said cuts at both edges of the ball of the sole are turned over and the edge of the upper is 60 stitched to the said turned-over portions of the sole. To do this stitching quickly I have devised the machine herein described. The overturned part of the inner sole along the ball thereof and the upper are interposed between the narrow portion e' of the presser-foot and the narrow portion 2 of the post, the hooked parts e² and 3 acting as gages against the inner sole on the bottom of the last and against the upper on the last to determine 65 the distance of the seam in the said turned-over portions from the main edge of the inner sole. The edge of the overturned part of the sole stitched to the upper is subsequently 70 cut off, so that when the inner sole is being 75 sewed to the outer sole along the ball of the sole the stitches pass for a part of the length of the shoes only through the outer sole and upper, as in the said patent. To do this 80 sewing automatically I have provided the 85 post with an ear f⁴, in which is placed the fulcrum f⁵ of the lever f⁶, provided at its upper end with a blade or cutter f⁷. The lower end of the lever f⁶ is forked to embrace 90 an eccentric or cam projection g, (represented by dotted lines, Fig. 1,) which projection is embraced by the said lever, the said projection in the operation of the rock-shaft c⁴ actuating the lever f⁶, causing the blade to trim the sole and upper parallel to the seam. The 95 foot f² of the post is attached to the framework by a bolt f³. The post has an attached shield or guard S, against which the face of the inner sole on the last is held, while the portions of the inner sole and upper to be 100

stitched together are put into position between the top of the post and the presser from the front of the machine. It will be noticed that the top of the rest and bottom of the foot are inclined backwardly from the front of the machine to thus insure the retention of the lip of the inner sole on the post and keep the face of the inner sole up against the shield.

10 The machine herein described will in practice be provided with the usual thread-guide to present a thread to the hook of the needle and with usual tension mechanism for the said thread.

15 I claim—

1. The combination, with the needle-bar and the needle therein and the guard or shield for the face of the inner sole, of a presser-foot having its under side beveled and a rest hav-

20 ing its upper side beveled, to operate substantially as described.

2. The combination, with a needle-bar, a needle therein, and a presser-bar, of a narrow

foot e^2 , having a hooked toe e^3 , and a post having a narrow top with a projection 3 , the under side of the said presser-foot and the top of the said rest being beveled, as represented, to operate substantially as described.

3. The combination, with the needle-bar and the needle therein and the guard or shield 3c for the face of the inner sole, of a presser-foot having its under side beveled and a rest having its upper side beveled, and with a blade or cutter, a lever located below the top of the post, and means to actuate the said lever to 35 trim the inner sole and upper parallel to the line of stitching, uniting the said inner sole and upper along the ball of the shoe, substantially as described.

In testimony whereof I have signed my 40 name to this specification in the presence of two subscribing witnesses.

GEO. A. STILES.
